UNITED STATES PATENT OFFICE.

OTTO SPAHR, OF PHILADELPHIA, PENNSYLVANIA.

SELF-HEATING SAD-IRON.

1,237,568.

Specification of Letters Patent. Patented Aug. 21, 1917.

Application filed September 16, 1914. Serial No. 861,946.

To all whom it may concern:

Be it known that I, OTTO SPAHR, a citizen of the United States, and resident of Philadelphia, county of Philadelphia, State of Pennsylvania, have invented certain new and useful Improvements in Self-Heating Sad-Irons, of which the following is a specification.

My invention relates to self-heating sad irons in which a gaseous fuel is used as the heating medium and has for its object to provide such irons with a simple and efficient means for producing a spark in the interior thereof whereby the gaseous fuel issuing from the burner may be quickly ignited when desired. Other objects of my improvement will appear from the description hereinafter and the features of novelty will be pointed out in the appended claims.

Reference is to be had to the accompanying drawings in which Figure 1 is a side elevation of an iron partly in section including my improvement; Fig. 2 is a plan view; Fig. 3 is a cross-section on the line 3—3 of Fig. 1; Fig. 4 is a similar view showing a different form of sparking device. Fig. 5 is a plan view of the body of an iron showing another form of sparking device; Fig. 6 is a cross-section thereof on the line 6—6 of Fig. 5 and Fig. 7 is a detail sectional view.

My improvement may be combined with any type of self-heating iron employing a gaseous fuel as a heating medium, the illustration as an example showing an iron comprising a hollow body 10 provided with an air inlet 11 and outlets 12 for the products of combustion. A cover 13 is pivotally connected at 14 with the body 10 so as to be movable relatively thereto in a plane parallel with the bottom of the iron and is provided with a suitable handle 15 whereby the iron may be manipulated as a whole or the cover 13 moved relatively to the body 10. Any suitable means may be used for maintaining the cover 13 in its closed position, the drawings showing a resilient catch 16 mounted at the rear end of the body 10 and arranged to engage and hold the rear edge of said cover 13 in the closed position of the latter.

A burner 17 having jet apertures 18 is located within the body 10 and forms part of or is connected with a tube 19 located exteriorly of the iron and having a nipple 20 whereby said burner and tube may be suitably connected with a source of fuel supply.

As shown in Figs. 1, 2 and 3, the sparking or ignition means comprises a bracket 21 preferably detachably secured within the body 10 in any suitable manner and provided with a projection 21^a adapted to detachably or removably receive a sleeve or socket 22 in which is located a section 23 of pyrophoric metal or other material capable of producing a spark under certain conditions to be more fully explained hereinafter. The pyrophoric metal or other material 23 is fixed in the socket 22 in any suitable manner as by friction and in the example shown projects upwardly from the bracket 21 and is adapted to engage a roughened or cutting surface 24 carried by the cover 13 and depending for instance from a support 24^a connected with the lower surface of said cover, preferably so as to be removable, as shown in the drawings. The portion of the bracket 21 which carries the socket 22 is preferably somewhat resilient so that the pyrophoric metal or other material 23 will be pressed into firm engagement with the surface 24 during the entire period of usefulness of each section of metal or other material 23.

In this form of my improvement each time the cover 13 is swung on its pivot 14 relatively to the body 10 the surface 24 will pass over the metal or other material 23 and will cut finely divided particles therefrom which quickly combine with the oxygen in the air and produce a spark or sparks. The metal or other material 23 and the cutting surface 24 are so located relatively to the burner 17 as to direct the said spark or sparks into contact with the fuel issuing from the jet openings 18 which fuel is in this manner quickly ignited.

In Fig. 4 a bracket 21^c similar to the bracket 21 carries a tube 25 having a roughened or cutting wheel or surface 26 rotatably mounted at its one end, the said tube 25 as illustrated extending parallel with the lower surface of the cover 13. A section of pyrophoric metal or other material 23 is located in said tube 25 and is maintained in contact with the wheel or surface 26 in any suitable manner as by means of a coil spring 27, an adjustable cap 28 being provided for maintaining said spring in said tube 25 and for adjusting its tension if desired, and for permitting the insertion or removal of the pyrophoric metal or other material 23 from the tube

25. In the illustrated example the wheel or surface 26 is arranged to frictionally engage the inner surface of the cover 13, the carrying portion of the bracket 21^c in this case being also preferably resilient so as to maintain said wheel 26 in proper frictional engagement with the actuating surface of the cover.

In this form each time the cover 13 is moved on its pivot 14 the wheel 26 will be rotated and in co-operation with the pyrophoric metal or other material 23 will produce a spark or sparks whereby the fuel issuing from the jet openings 18 will be quickly ignited in the same manner as in the first form of my improvement.

In both of the forms so far described the spark or sparks is or are automatically produced each time the cover 13 is manipulated relatively to the body 10 and no other operation is necessary to properly ignite the fuel. By delaying the actuation of the cover more or less after the fuel has been turned on the supply of fuel to the body of the iron before ignition takes place may be regulated as will be clearly apparent. The cover may of course be successively manipulated as often as necessary to secure ignition of the fuel although in most cases a single actuation will be found sufficient for this purpose. It will of course be understood that the location of the parts may be reversed if desired, or in other words that those elements which, as shown, are positioned on the body may be carried by the cover while the elements carried by the cover may be mounted on the body.

In Fig. 5 I have shown an ignition device operating independently of the cover and comprising a bracket 21^b having a tubular portion 25^a in which a section of pyrophoric metal or other material 23 is located, the latter being arranged in contact with a roughened or cutting wheel or surface 26^a rotatably mounted on said bracket 21^b. A projection 29 extends radially from said wheel or surface 26^a and is connected with an actuating rod 30 extending through an aperture 31 in a wall of the body 10 and terminating in an external handle 32 as clearly shown in Fig. 5. One or more coil springs 33 may surround the shaft on which the wheel 26^a is located and engage said projection 29 and the bracket 21^b respectively, said spring or springs serving to rotate said wheel 26^a in one direction as will be more fully described hereinafter. It will of course be apparent that any other means adapted to accomplish the same result may be substituted for the spring or springs 33 if preferred.

In using this form of my improvement the actuating rod 30 is drawn outwardly by means of the handle 32 to rotate the wheel 26^a against the tension of the springs 33 and then released. As soon as the rod 30 is

released the springs 33 will snap the projection 29 and the wheel or surface 26^a back in a reverse direction so that said wheel or surface will rapidly pass over the metal or other material 23 and produce a spark or sparks in the same manner as hereinbefore set forth. These sparks will contact with the fuel, which previously has been turned on and is issuing from the jet openings 18 and will thus quickly ignite the same. If a single operation of the rod 30 fails to produce the desired ignition the actuation thereof may be successively repeated until the desired result has been attained. It will be seen that no operation of the cover 13 is necessary to operate this last form of my invention although it will be obvious that other methods of operating same may be adopted if desired.

In all the forms of my improvement the sparking means comprises a relatively stationary and a movable means so located as to throw the spark or sparks into contact with the gaseous fuel issuing from the jet openings of the burner so that a quick ignition of the fuel is brought about and unnecessary work is entirely eliminated. My improvement in all of its forms may be readily and quickly combined with existing types of self-heating gas irons without necessitating any change in the construction thereof and absolutely does away with the necessity for using matches, tapers or the like when it is desired to use the iron. The danger of burning the person using the iron is thus obviated and the operations necessary to bring the iron to a condition ready for use are greatly reduced and simplified.

In Figs. 1, 2 and 3 the pyrophoric metal or other sparking means may be removed when worn out and replenished by simply removing and replacing the sleeve or socket 22 from the projection 21^a while the same result may be accomplished in Fig. 4 by simply first removing the cap 28 and coil spring 27 from the tube 25 to permit the worn sparking means to be removed and a new one inserted after which the spring and cap are replaced. In both of these forms it is therefore unnecessary to remove the entire device from the iron when it is desired to substitute a new sparking means for a useless one.

Various changes in the specific forms shown and described may be made within the scope of the claims without departing from the spirit of my invention.

I claim:

1. In a self-heating sad iron the combination of a hollow body, a perforated gaseous fuel burner therein, a pivoted cover on said body movable relatively thereto, abrasive means located on said cover near its free end and a relatively stationary section of pyrophoric metal located in operative relation to said abrasive means, the latter being adapted

to frictionally engage and pass across said section of pyrophoric metal each time the cover is pivotally actuated whereby a spark is produced to ignite the fuel issuing from the burner.

5 2. In a self-heating sad iron, the combination of a hollow body, a perforated gaseous fuel burner therein, a pivoted cover on said body movable relatively thereto in a horizontal plane, an abrasive member located on said cover near its free end and a relatively stationary section of pyrophoric metal located in coöperative relation to said abrasive member, the latter being adapted to frictionally engage and pass across said section of pyrophoric metal each time the cover is pivotally actuated whereby a spark is produced to ignite the fuel issuing from the burner.

10 15 3. In a self-heating sad iron, the combina-

tion of a hollow body, a perforated gaseous fuel burner therein, a relatively stationary section of pyrophoric metal in said body, a resilient carrier for said section, a cover movably connected with said body, a support 25 depending from said cover and an abrasive member carried by said support and adapted to frictionally engage and pass over said section of pyrophoric metal each time said cover is pivotally actuated whereby a spark 30 is produced to ignite the fuel issuing from the burner.

In testimony whereof I have hereunto set my hand in the presence of two subscribing witnesses.

OTTO SPAHR.
